United States Patent Office.

CHARLES J. MILLER, OF PHILADELPHIA, PENNSYLVANIA.

Design No. 2,869, dated January 28, 1868.

DESIGN FOR A TRADE-MARK.

The Schedule referred to in these Letters Patent and making part of the same.

TO ALL WHOM IT MAY CONCERN:

Be it known that I, CHARLES J. MILLER, of the city and county of Philadelphia, and State of Pennsylvania, have invented a new and useful Design for a Trade-Mark; and I do hereby declare the following to be a clear and exact description of the nature thereof, sufficient to enable others to fully understand the same, reference being had to the accompanying drawings, making part of this specification, and which represent the design illustrating my invention.

I intend to apply the same to packages of chewing-tobacco as a trade-mark for a peculiar brand, to be known as the "Monitor Chewing."

In general description, my design consists of a monitor of the original form, and which is lying or sailing in the foreground in rough water. A flag-staff is placed fore and aft, from both of which floats the national standard. From the deck of the vessel arises the turret, through which protrudes its gun, which has just been discharged against the enemy's vessel, which is not distinguishable through the smoke. An air-pipe is on one side of the turret, and a steam-pipe on the other side, and from the latter is seen the escaping exhaust steam, ascending in puffs. The monitor is provided with the usual side-rails or bulwarks, and has its deck entirely cleared for action. In the distance is perceived a man-of-war, engaged in battle with the monitor, and having discharged one of its side guns in line against the turret. The smoke of battle is rising on the starboard side of the monitor, and at the bow of the man-of-war.

Beneath the above-described scene are placed, in block letters, the words "Monitor Chewing," which are enclosed by a border, having rounded corners, and a small ornamentation on its sides.

The above design may be printed in any desired colors, and of size to correspond with the weight of the package to which it is applied.

Having thus described my invention, what I claim as new, and desire to secure by Letters Patent, is—
The design for a trade-mark, substantially as herein described and shown in the drawings.

To the above I have signed my name, this twenty-seventh day of November, 1867.
